ALLEN D. CARDWELL, OF ROCKVILLE CENTER, NEW YORK.

MEANS FOR VARIABLY CONTROLLING ELECTRICAL INSTRUMENTS.

Application filed June 27, 1925. Serial No 39,997.

In a co-pending application I have set forth improvements in electrical instruments embodying complementary elements movable relatively one to another and a control member for the movable element, with means operatively connecting the controlling member with the movable element for moving the latter relatively to the other element of the instrument in such a way that for given movements of the controlling member the constants of the circuit of the instrument will be changed in conformity with the movement of the controlling member. In other words, the arrangement is such that when the controlling member is given a uniform movement of constant character, or of equal changes or distances, the movable element of the instrument will be moved in a more or less variable manner to effect changes in the constants of the circuit to conform with a uniform wave length of the circuit, or to conform with a uniform frequency variation of a circuit, or to conform with a uniform logarithmic change in the circuit, applicable in electrical instruments such as variable air condensers, variable inductances, such as variometers, variable couplers, such as vario-couplers, and variable resistances, such as rheostats.

An object of my invention is to provide simple and improved means operatively connecting the controlling member with the movable element of an electrical instrument of the class before set forth in such a way that the movable element of the instrument may be given more or less movement relatively to a given extent of movement of the controlling member, which latter may be rotated 360° , or approximately so, for 180° rotation of the movable element, or approximately so, or in any other desired ratio, with the controlling element located concentrically with respect to the movable element, whereby for substantially what may be called coarse movement of the controlling member relatively fine movements of the movable element may be given at some portions of its operation and relatively coarse or more extensive movements of the movable element may be given at other points of its rotation, and other movements equal to or variable respecting the extent of movement

of the controlling member may be given to the movable element according to the characteristics, requirements and constants of the circuit to be controlled.

In the example of my invention illustrated in the accompanying drawings I provide an electrical instrument such as a variable air condenser, having a stationary element and a movable element respectively comprising spaced plates, the movable element having a shaft for rotating the same, a controlling member operative independent of the movable element and journaled concentric therewith, an arm connected with said shaft, a stationary cam plate, a rotative cam plate connected with the controlling member, whereby the cams or cam grooves of said plates may assume different angular positions relatively to one another, and means cooperative between the arm and the cam plates for causing operation of the movable element in accordance with the relative angular relation of the cams or cam grooves respecting one another for imparting to the movable element desired angular movements respecting its complementary member derived from given angular rotary movements of the controlling member.

My invention also comprises novel details of improvement that will be more fully hereinafter set forth and then pointed out in the claims.

Reference is to be had to the accompanying drawings forming a part hereof, wherein

Fig. 1 is a face view illustrating a panel in connection with which my improvement is applied;

Fig. 2 is a vertical section on line 2, 2, in Fig. 1;

Fig. 3 is a detail perspective view of the actuating arm;

Fig. 4 is a cross section through Fig. 3;

Fig. 5 is a partly broken face view of parts in the position shown in Fig. 1, the controlling member or dial being omitted;

Fig. 6 is a section on line 6, 6, in Fig. 5, illustrating also the controlling member or dial;

Fig. 7 is a face view illustrating the stationary cam plate;

Fig. 8 is an inverted face view of the

movable cam plate that is represented partly broken in Fig. 5;

Fig. 9 is a view illustrating the cam plates in a position different from Fig. 5;

Fig. 10 illustrates the rotative cam plate in the position it assumes when the actuating arm has been moved 180° from the position shown in Fig. 5; and

Fig. 11 is a perspective detail of a spring washer.

Similar numerals of reference indicate corresponding parts in the several views.

I have illustrated my improvements in connection with a variable air condenser 1, which may be of any well known construction, having a stationary element 2 comprising spaced plates 3 and a movable element or rotor 4 having spaced plates 5 carried by a shaft 6. In the example illustrated the condenser is provided with semi-circular movable plates 5 whereby there is afforded an approximately uniform variation of capacity for uniform angular movements of shaft 6 throughout 180° rotation, and such plates will admit a maximum capacity for a given over-all dimension of condenser, since the full radii of the rotor plates are effective. In Figs. 2 and 5 the condenser plates are fully interleaved as in full capacity, (in dotted lines), said plates being represented in Fig. 9 as in partial capacity position, and in Fig. 10 as at minimum capacity position. In other words, the condenser illustrated is of the variety commonly called a straight line capacity condenser.

At 7 is a controlling member or what is commonly called a knob and dial adapted to be manually operated to actuate the movable element or rotor 4 relatively to the stationary element 2. At 8 is an actuating arm secured to shaft 6 of the movable element or rotor, as by means of a screw 9. Arm 8 preferably has a tubular hub or sleeve 8^a receiving shaft 6. The arm 8 is shown provided with an index or pointer 10 adapted to indicate the angular positions of the arm 8 and the rotor on any arbitrary scale. In the example illustrated 180° of rotation of shaft 6 is represented by 100 divisions of the scale on the panel, at A, and thereby the relative positions of the movable element or rotor plates 5 with relation to the stationary plates 3 of the condenser may be determined. I provide means for variably operating the arm 8 and the movable element from given or uniform movements of the controlling member or dial 7. For such purpose I provide a stationary plate 11, which may be secured to a panel or other support 12, as of a radio set as by screws 12^a in connection with which the condenser or electrical instrument may be supported in any suitable way, as by mounting posts 2^a secured to the panel by means of the screws 12^a. The shaft 6 projects through

an opening in the panel and through a clearance hole 13 in plate 11, (Fig. 2). The plate 11 is provided with a cam groove or raceway 14. At 15 is a rotative plate or disk provided with a cam groove or raceway 16 ^{7a} and mounted to rotate concentrically with respect to the axis of the movable element or rotor 5, and the plate 15 is provided with a hub or sleeve 17 mounted to rotate concentrically with the axis of the movable element or rotor 5 and shown journaled upon the hub or sleeve 8^a. I have shown a nut 18 upon hub 8^a operative in conjunction with a spring washer 19 that surrounds said hub and bears against the hub or sleeve 17 for the purpose of retaining plate 15 spring-pressed toward cam plate 11. The controlling member or dial 7 is shown provided with a bore 7^a enclosing the adjacent portions of parts 6, 8^a and 17, and with a skirt ^{8a} portion 7^b surrounding the plates 11 and 15, (Fig. 2). Controlling member or dial 7 is rigidly connected to the cam disk 15. I have shown said parts connected by means of screw 20 carried by the controlling member and engaging the hub 17, whereby when the controlling member or dial is rotated in one direction or another the cam plate 15 will be correspondingly rotated. I utilize the rotation of cam plate 15 to control the rotation of the movable element or rotor 4 relatively to the stationary element 2. For such purpose I provide a movable member preferably in the nature of a ball 21 adapted to operate in the cam grooves 14 and 16, ¹⁰⁰ which member or ball is guided to travel longitudinally along arm 8 while causing the latter to rotate. To retain said member or ball 21 and arm 8 the latter is provided with a longitudinal slot 8^b receiving the ball, the edges of which slot diverge from the outer surface of the arm inwardly in the nature of a raceway to retain the ball in operative position in the slot. The arm is shown longitudinally slit at 8^c so that the arm may be spread to permit insertion of the ball, and the pointer 10 is shown retained between the two portions of the arm by means of rivets 22. The pointer is bent laterally at 10^a so that its outer end may extend beyond the plates 11 and 15 and project between the inner edge of the controlling member or dial 7 and the panel 12, (see Fig. 6). When the parts described are assembled, as indicated in Fig. 2, the cam disks will be so related that the member or ball 21 will be located in the cam grooves of the disks, since such grooves at some relative points always coincide and oppose one another. ¹¹⁰

It will be observed that the cam groove 14 is of such a character as to partially surround the axis of the movable element or rotor 4 with one portion of the cam groove at 14^a nearer to said axis than the other por- ¹²⁰ ¹³⁰

tion 14^b, the cam groove being designed to aid in causing the arm 8, and thereby the movable element or rotor, to travel at variable speeds. The cam groove 16 has its portion 16^a nearer the axis of disk 15 than its portion 16^b. The radial distance from the axis of shaft 6 is the same respecting the termini 14^a, 16^a of the grooves 14, 16 and also the same regarding points 14^b and 16^b.

5 When the rotor is in the full capacity or minimum capacity position respecting the stationary element 2 the cam groove 16 will lie upon the side of the axis of the rotor opposite the groove 14, and when plate 15 is rotated in one direction or another the cam groove 16 will be moved with the disk in such a manner as to cause the groove 16, and thereby cause the ball 21, to travel correspondingly, since the walls at the sides of the cam grooves engage the ball and push it, the ball in turn causing arm 8 to correspondingly rotate and thereby the movable element or rotor of the condenser is correspondingly actuated. In the position of the parts shown in Fig. 5 the condenser elements are in maximum capacity position with the ball 21 engaging both the cam grooves at their respective points 14^a and 16^a.

10 If the controlling member or dial be rotated counter-clockwise in Fig. 5 the cam groove 16 will be caused to advance in the direction of the cam groove 14 and thereby the ball 21 will be correspondingly moved and the rotor plates 5 will be moved in the direction from maximum toward minimum capacity. In the example illustrated the cam groove 14 is laid out as a full logarithmic spiral so that equal angular positions of ball 21 in said cam groove from point 14^a to 14^b will be represented by equal increments in radius from the axis of shaft 6. The orbit of ball 21 will comprise 180° rotation about shaft 6. Cam groove 16, on movable plate 15, is laid out so that the orbit of ball 21 will be restricted to 180° movement in such groove and around the axis of shaft 6. Cam groove 16 has been laid out so that its starting point 16^a will be the same distance from the axis of shaft 6 as point 14^a of cam groove 14, and point 16^b will be the same radial distance from said axis as point 14^b of cam groove 14. Intermediate positions on cam groove 16 will vary between these extreme minimum and maximum radial dimensions according to a curve which will fix the point of intersection of the centers of the two cam grooves, or the center of the ball rolling in such grooves, at various points required in accordance with the angular rotation of cam groove 16 as desired. For example, if it is required that the movable element or rotor be rotated in accordance with the square of half of the angle of rotation of plate 15 the point of intersection of the two cam curves

will rotate around the axis of shaft 6 in accordance with the above mentioned law as plate 15 is revolved through 360°. Inasmuch as the movement of ball 21 carries the arm 8 any angular movement of ball 21 about the axis of shaft 6 will be imparted directly to said shaft and thereby to the rotor element of the control device. The varying positions of the ball radially from the axis of shaft 6 are permitted because of the longitudinal ball race on arm 8. The position of the ball along said race does not alter the angular position of the arm 8. From the shape of curve 16 it will be seen that a relatively large movement of cam plate 15 will be required in order to produce comparatively small angular movement of ball 21 when the two cam plates are moved from the position illustrated in Fig. 10 clockwise; but as the cam plate 15 is rotated further in a clockwise direction the point of intersection of the two curves will have a greater angular velocity, thereby causing an increased rotation of shaft 6 for the same angular rotation of cam plate 15. When cam plate 15 is rotated in an opposite direction or counter-clockwise the converse is true. In the example illustrated when both cam slots comprise 180° about the axis of shaft 6 it is self-evident that a rotation of 360° only is permitted plate 15, providing the ball 21 is retained within grooves 14 and 16, for at one position the ball will be located as illustrated in Fig. 5 at the minimum radial points of both cam grooves and cam plate 15 will be prevented from further clockwise rotation by said ball. When cam plate 15 is rotated in a counter-clockwise direction from the point illustrated in Fig. 5 the ball 21 will follow the orbit of the groove 14, and after 360° rotation of cam slot 16 the ball 21 will again intercept the rotation of cam plate 15 and restrict its movement, inasmuch as it will be at the opposite end of the cam slots, namely at points 14^b and 16^b in the respective cams.

15 Pins 23 projecting from plate 11 are located in the path of arm 8 and limit its rotation from zero to maximum positions. By laying out cam grooves 14 and 16 in various forms any variable relative angular movement between controlling member or dial 7 and the controlled shaft 6 may be attained. For example, if it is required that a greater rotation of plate 15 be desired for a smaller rotation of shaft 6 the cam slot 16 should approach the arc of a circle with the center at the axis of shaft 6; and if the desired motion is so slow as to require a very long slot 16 the same may be accomplished by having slot 16 comprise more than 180°, so that said slot may comprise 540°, in which case the total movement would be two revolutions of the controlling member or dial or 720° total for 180° rotation.

tion of shaft 6. In case greater than 180° of rotation of shaft 6 be required such may be obtained by increasing the angular length of cam slot 14, and angular velocities of shaft 6 variable as may be desired from position to position of plate 15 may be effected by the proper intersection of the stationary and movable cam grooves.

In the example illustrated I have shown 10 semi-circular rotative plates 5 of the so-called straight line capacity type. Any shape plate may be used and corresponding corrections incorporated in the shapes of the cam grooves to compensate for or operate 15 in conjunction with the differently shaped rotor or stationary plates or other factors of the controlled element designed, for which compensation may be desired. The contour of the cam grooves 14 and 16 may 20 be such as to cause variable rotation of the rotary element of the electrical instrument or condenser in conformity with given or uniform angular rotative movements of the controlling member or dial for producing 25 changes in the capacity constants of the circuit to conform with a uniform wave length of the circuit, or to conform with a uniform frequency variation of the circuit, or to conform with a uniform logarithmic change in 30 the circuit. My improvements are applicable not only in variable air condensers but to the control of variable inductances, such as variometers, variable couplers, such as vario-couplers, and in variable resistances, 35 such as rheostats, wherein the angular rotation of the movable element thereof may be variable in conformity with a given angular rotation of the controlling member or dial.

On panel 12 I have represented an arbitrary scale from zero to 100, indicated at A, with equal divisions throughout the 180° between the minimum and maximum. The pointer 10 travels with relation to said scale 45 and the various positions of the rotor element can be read directly on such scale. The dial 7 is shown graduated in twenty divisions between 10 and 200, reading in a counter-clockwise direction, with the minimum and maximum position opposite the 50 lubber line at the zero position of the scale on panel 12. The equal angular movements of the dial 7 will represent equal increments of scale on such dial, and index pointer 10, 55 will travel from zero to 100 on panel 12 while dial 7 is turned through 360°. However, index pointer 10 will not travel over corresponding degrees of numerals on its dial for equal movement of dial 7 but will 60 move with increasing velocity in accordance with the contour of the respective controlling cam grooves and in conformity with the given angular movements of the dial. The index on the dial 7 may be so divided 65 as to indicate equal wave lengths, equal in-

creases in frequency, or equal logarithmic increments, or any other units to be designated.

In accordance with the example illustrated and assuming that the rotor plates 5 are in 70 the position of minimum capacity and that the controlling member or dial 7 is rotated manually in a clockwise direction (from the position of the rotor plates and pointer 10 shown in Fig. 10), the rotation of the controlling member or dial for a given distance, say 5° on scale A, will produce a corresponding directional movement of the rotor but of less angular distance than the controlling member. For each further degree of rotation of the controlling member in the same direction the rotor 4 will be rotated at an increasing angular distance but less than the angular distance rotated by the controlling member, so that the rotation of the 80 rotor is variable with respect to given or uniform angular distances of rotation of the controlling member, which permits the operator to actuate the controlling member with relatively coarse movements for all positions 85 along the scale with the rotor actuated for distances respecting the stationary element 2 according to the required relative positions of the movable and stationary elements 90 of the instrument with respect to wave lengths, kilocycles, or other characteristics or constants of the circuit. By changing the contour of one or both cam grooves of the plates or members 11 and 15 the movement 95 imparted to the movable element or rotor 4 by the controlling member or dial may be less than, equal to, or more than given movements of the latter at any desired positions 100 of such parts.

Having now described my invention what I claim is:

1. An electrical instrument comprising complementary elements movable relatively one to another, a controlling member rotative independently of the movable element, 110 a stationary cam member, a second cam member rotative relatively to the stationary cam member and connected with the controlling member for operation thereby, an arm connected with the movable element, and a ball 115 cooperative with said arm and with said cam members and movable relatively thereto for actuating the movable element at variable distances for given distances of rotation of the controlling member for producing 120 equal changes in the electrical circuit in which the instrument is used, the arm having guiding means for the ball, whereby rotation of the movable cam member will cause the ball to travel along the arm for variably 125 rotating the movable element in conformity with given movements of the controlling member for changing the constants of the circuit.

2. An electrical instrument comprising 130

- complemental elements movable relatively one to another, a controlling member rotative independently of the movable element, a stationary cam member, a second cam member 5 rotative relatively to the stationary cam member and connected with the controlling member for operation thereby, an arm connected with the movable element, and a ball cooperative with said arm and with said cam members and movable relatively thereto for 10 actuating the movable element at variable distances for given distances of rotation of the controlling member for producing equal changes in the electrical circuit in which the instrument is used, the arm having a longitudinal slot receiving the ball and provided with means to retain the ball operatively along the arm, whereby rotation of the movable cam member will cause the ball to travel 15 along the arm for variably rotating the movable element in conformity with given movements of the controlling member for changing the constants of the circuit.
3. An electrical instrument comprising 20 complemental elements movable relatively one to another, a controlling member, a plate secured relatively to the movable element and provided with a cam groove, a second plate rotative with respect to the first named plate and provided with a cam groove opposing the first named groove in position to intersect the latter, means operatively connecting the controlling member with the second named cam plate for rotating the latter, an arm connected with the movable element, and means movably operative in said cam grooves and adapted to operate the arm in conformity with the intersecting positions of the cam grooves during rotation of the controlling member for operating 25 the movable element variably with respect to given movements of the controlling member in such a manner that equal movements of the controlling member give equal changes in the circuit in which the instrument is used.
4. An electrical instrument comprising 30 complemental elements movable relatively one to another, a controlling member provided with an actuating arm, a stationary plate having a cam groove extending partially around the axis of the movable element, a plate mounted to rotate concentrically with respect to said axis and provided with a cam groove adapted to oppose the first named 35 cam groove and to coincide therewith in different positions of the second named plate respecting the first named plate, and means cooperative with said arm and movably operative in said cam grooves for actuating 40 said arm and thereby the movable element variably with respect to given movements of the controlling member in such a manner that equal movements of the controlling member give equal changes in the circuit in 45 which the instrument is used.

ALLEN D. CARDWELL.
